Assistant Examiner — Matthew Bird

(57) **CLAIM**

The ornamental design for a tower fan as shown and described.

DESCRIPTION

FIG. 1 is a perspective view of a tower fan showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the tower fan that form no part of the claimed design. The “DREO” logo forming no part of the claimed design is a registered trademark of HESUNG INNOVATION LIMITED.

1 Claim, 7 Drawing Sheets
